UNITED STATES PATENT OFFICE

102,890

DESIGN FOR AN OIL BURNER OR SIMILAR ARTICLE

Nelson Hayward, San Francisco, Calif., assignor
to Ray Oil Burner Co., San Francisco, Calif.,
a corporation of Delaware

Application August 5, 1936, Serial No. 64,265

Term of patent 14 years

To all whom it may concern:

Be it known that I, Nelson Hayward, a citizen of the United States, residing in the city and county of San Francisco, State of California, have invented a new, original, and ornamental Design for an Oil Burner or Similar Article, of which the following is a specification, reference being had to the accompanying drawing, forming part thereof.

Fig. 1 is a side perspective view of an oil burner, showing my new design, and illustrating the burner body swung away from the burner hinge plate which is adapted to be secured to a furnace wall;

Fig. 2 is a view similar to Fig. 1, but looking

at the opposite side of the burner, and illustrating the burner body against the hinge plate, and the fuel and air control lever in a different position from that shown in Fig. 1;

Fig. 3 is a perspective view of the burner, looking at the rear; and

Fig. 4 is another perspective view of the burner, looking at the rear but at an angle different from that in Fig. 3.

I claim:

The ornamental design for an oil burner or similar article, substantially as shown and described.

NELSON HAYWARD.
